UNITED STATES PATENT OFFICE.

JOHN C. DOANE, OF HARTFORD, CONNECTICUT, ASSIGNOR TO UNDERWOOD TYPEWRITER COMPANY, OF NEW YORK, N. Y., A CORPORATION OF DELAWARE.

TYPE-WRITING MACHINE.

1,248,287.

Specification of Letters Patent. Patented Nov. 27, 1917.

Application filed February 27, 1917. Serial No. 151,156.

To all whom it may concern:

Be it known that I, JOHN C. DOANE, a citizen of the United States, residing in Hartford, in the county of Hartford and State of Connecticut, have invented certain new and useful Improvements in Type-Writing Machines, of which the following is a specification.

This invention relates to an improvement in typewriting machines and more especially to a combined work-holder and ribbon guard, coöperating with the line-gage to maintain a work-member in proper position on the platen.

When it is desired to write almost on the very bottom edge of the work-sheet or card when writing in lower-case, the line-gage assists in holding the work-member on the platen. If the platen should be shifted to upper-case, however, where the line-gage does not move to upper-case position of the platen, the lower edge of the work-member sometimes moves away from the platen, and in returning to lower-case position catches on the line-gage and also on the casings for the ribbon spools. To overcome this difficulty, there is provided a holder which comprises a pair of fingers projecting considerably above the top edge of the line-gage, which corresponds substantially with the base of the line of typewriting. These fingers are located on opposite sides of the printing point, so as not to interfere with the striking of the type-bars, and engage the work-member at such a point as will hold the same snug on the platen even to the last line of writing. They also act to maintain stiff cards in snug position on the platen.

Connected with the support for the fingers, there is provided a pair of guards whose upper limits of reach are considerably above the top edge of the line-gage, and thus above the typewritten line. They extend to such a position as to deflect the lower edge of the work-sheet when moving from upper to lower-case position, so that it will not catch on the casings for the ribbon spools. These guards are yieldingly mounted, so that as the sides of the carriage pass over them, they are depressed out of the way, as it is desired that their range

shall be above the lowest projection of the sides of the carriage in whose path they lie.

Other features and advantages will hereinafter appear.

In the accompanying drawings,

Figure 1 is a skeleton perspective view showing the device in its normal position with the carriage about midway of its travel.

Fig. 2 is a vertical section taken from front to rear, with parts omitted to simplify the showing. In this view the platen is in lower-case position.

Fig. 3 is an enlarged detail view in front elevation, with parts broken away to show the underlying structure. The carriage is shown as having traveled considerably toward its extreme right-hand position, showing in full-lines, the left-hand guard depressed to clear the frame of the carriage, and in dotted-lines, the position the guard normally occupies when the carriage frame is out of the way.

Fig. 4 is an enlarged top plan view, showing the relation of the guards to the casings for the ribbon spools.

The device is shown as attached to the usual Underwood typewriting machine, in which numeral keys 1 and alphabet keys 2 depress key-levers 3, to rock bell cranks 4, so as to swing type-bars 5 up rearwardly against the front side of the platen 6 mounted to rotate on a carriage 7. The carriage 7 has the usual step-by-step travel under the control of an escapement mechanism indicated in general at 8. This escapement mechanism includes a rack 9 mounted on the carriage 7, engaging a pinion 10, controlled in its rotation by an escapement wheel 11, which in turn is controlled by a pair of dogs 12. The dogs 12 are rocked back and forth at each actuation of a key, by means of a universal frame 13, which is engaged by heels 14, one of which is provided on each of the type-bars 5.

The type-bars 5 are provided with two sets of characters 15 and 16, corresponding to upper and lower-case writing. Normally, the platen 6 is in a position to write lower-case characters, it being raised by shift keys 17 to upper-case position when it will co-operate with the upper-case characters 15.

For this purpose, the platen 6 is mounted on an inner carriage or platen frame 18, which is supported on the main carriage 7 by pivoted arms 19. The inner carriage or platen frame 18 is also provided with rollers 20, which ride on a shift rail 21. The shift rail 21 is mounted on a rocking shift frame 22, which is operated from either of two shift keys 17. The said keys when depressed, 10 rock levers 23 to swing arms 24 carried thereby forward, and thus rock the shift frame 22, which in turn raises the platen 6.

The type-bars 5 do not strike the work-sheet indicated at 25 directly, but are guided 15 to strike a carbon ribbon 26 which transfers an impression to the work-sheet 25 corresponding to the particular type key depressed. The ribbon 26 is threaded through the usual vibrator 27, and unwinds from 20 one and winds on the other of a pair of spools 28, depending upon a direction of travel of the ribbon. When the spool completely unwinds the direction of drive is reversed and the ribbon is wound from the 25 full spool to the empty spool. The spools 28 are mounted to rotate in casings 29 which assist in guiding the ribbon, and are protected to a certain extent from dust.

For the purpose of accurately positioning 30 the work-sheet or other work members on the platen 6, there is provided a line-gage 30. The line-gage 30 includes a pair of wing scales 31 mounted by means of hinge brackets 32 on the segment 33, which guides the 35 type-bars 5. The wing scales 31 are normally held with their top edges snug against the platen 6 by means of springs 34, which, however, permit them to yield, so as not to interfere with the case-shift movement of 40 the platen or with the travel of the carriage, besides allowing for different thicknesses of work members on the platen. The fact that the line-gage engages the platen, simply enables it to assist the usual feed rollers 35 45 in holding the work-members snug on the platen. This is especially true where the lower part of the work-member is being written on after it has passed beyond the control of the feed rollers 35.

50 In such a case, when the platen is shifted to its upper-case position, the lower edge of the work-sheet might escape from the line-gage 30, and when the platen is returned to lower-case position, it might come on the out 55 side of the gage 30 and perhaps catch on the casings 29 of the ribbon spool. To avoid this, deflecting and holding fingers 36 are provided between the wing scales and guards 37 provided at the sides of the wing scales.

60 The fingers 36 are mounted or formed on a support 38 shown and comprised in the form of a cross-piece 39, having angular reaches 40 inserted in slots provided in the heads 50 of pins 51. The pins 51 are reduced at their

lower ends to engage sockets provided in the, 65 segment 33. The fingers 36 are spoon-shaped, so as to present curved surfaces to the platen and thus to the work-sheet. They also are deflected inwardly toward the platen from their base up to their upper ends. 70

The support 38 also forms a mounting for the guards 37. For this purpose, there are provided extensions 52 projecting to the right and left from the reaches 40, and in a direction substantially parallel to the line 75 of travel of the platen. The guards 37 are pivotally mounted on extensions 52 at their inner ends, by means of pivot screws 53. The guards have lugs 54 projecting inwardly behind their pivot points to engage 80 the heads 50 of the pins 51, so as to determine their normal position. They are held in these normal positions by springs 55, which engage arms 56 on the guards at one end, and brackets 57 on the extensions 52 at 85 their other end.

The guards curve upwardly, so that the highest point of their top edges reach considerably behind the top edge of the line-gage 30. From these points they curve outwardly and downwardly in juxtaposition with respect to the ribbon spool casings 29. The guards are formed in the manner of sickles to enable them to be easily cammed down out of the way, when the carriage 95 frame travels over them, as indicated at 60 in Fig. 3. In this figure, it will be seen that the dotted-line position shows the normal raised position of one of the guards which is considerably above the line of travel of the 100 lower edge of the carriage frame, and that the guard can be depressed with the passage of the carriage frame in either direction without interference.

It will thus be seen that the fingers 36 105 will assist in guiding the ordinary work-sheet and will maintain a stiff work-member such as a card, in the proper position on the platen. It will further be seen that the guards 37 will prevent the disarrangement 110 of the work-sheet on the platen by accidental engagement with the ribbon spool casings 29.

Variations may be resorted to within the scope of the invention, and portions of the 115 improvements may be used without others.

Having thus described my invention, I claim:

1. The combination with a carriage having ends and a platen, of a type-action co-operating with said platen, a ribbon interposed between said type-action and said platen, spools for said ribbon, casings upon the machine frame for said spools, and guards mounted on the machine frame to prevent contact of work-members carried by said platen with said casings, said guards in the path of travel of said carriage ends,

and being mounted to yield when engaged by said carriage ends, to permit the travel of the carriage.

2. The combination with a traveling carriage, of a platen carried by said carriage, type-actions coöperating with said platen, a ribbon interposed between said type-actions and said platen, spools for said ribbon, casings for said spools, and guards for said 10 spool casings preventing the engagement of said casings with a work-sheet carried by said carriage, said guards normally lying in the path of travel of the said carriage, and being pivoted so as to be forced aside by 15 the carriage.

3. The combination with a carriage, of an up-and-down shiftable platen carried by said carriage, a stationary line-gage for said platen, type-actions coöperating with said 20 platen, a ribbon interposed between said type-actions and said platen, separated spools for said ribbon, casings for said spools, said line-gage mounted between said spools, and a pair of guards above the top edge of 25 said line-gage and extending beyond the ends thereof into proximity with the casings of said spools, in position to guide the lower edge of the work-sheet away from said casings and toward said platen at the down- 30 ward shift of the latter.

4. The combination with a typewriter frame, of a carriage traveling on said frame, a platen mounted on said carriage, a ribbon mechanism coöperating with said platen including casings in close juxtaposition to the line of writing on said platen, and a pair of guards pivoted at their inner ends centrally of said frame, and extending at their outer swinging ends in intervening position 40 between said casings and said platen, so as to act as deflectors preventing an engagement of a work-member carried by said platen with said casings.

5. The combination with a traveling carriage, of a platen mounted on said carriage, ribbon mechanism coöperating with said platen including casings in close juxtaposition to the printing line of said platen, and a pair of sickle-shaped guards bending in 50 toward their outer ends to a position between said casings and said platen, and yieldingly mounted, so that when their curved surfaces are engaged by said carriage, they will yield to permit free passage 55 of said carriage.

6. The combination with a platen, of a combined work-member holder and guard coöperating with said platen comprising a

body portion having a pair of fingers projecting upwardly therefrom, and a pair of 60 guides pivotally mounted on said body portion and bending arcuately toward the end of said platen when in a central position.

7. The combination with a type segment of a pair of pins mounted in said segment 65 having heads with sockets therein, a strip of metal having a cross-piece with a pair of fingers projecting therefrom, reaches bent with respect to said cross-piece and extending into said sockets, extensions projecting 70 from said reaches in opposite directions, and a pair of guards projecting outwardly from said extensions and being pivotally mounted thereon.

8. The combination with a type segment, 75 of a pair of pins mounted in said segment having heads with sockets therein, a strip of metal having a cross-piece with a pair of fingers projecting therefrom, reaches bent with respect to said cross-piece and extending 80 into said sockets, extensions projecting from said reaches in opposite directions, and a pair of guards projecting outwardly from said extensions and being pivotally mounted thereon, said guards having lugs thereon engaging the heads of said pins, arms on said 85 guards and springs connecting said arms and said extensions.

9. The combination with a platen, of a pair of card fingers for said platen, a type-bar segment, and supporting means for said card fingers comprising a cross-strip integral with said card fingers a pair of pins mounted in said segment and having grooved heads and reaches projecting from said strip 95 extending into said grooved heads.

10. The combination with a platen of a line-gage for said platen having its upper edge normally in engagement with said platen, and a pair of guards pivotally 100 mounted at their inner ends below the upper edges of said line-gage and curving upwardly, bringing the upper edges thereof considerably above the upper edges of said line-gage where the upper edges of said 105 guards curve downwardly to points considerably below the upper edges of said line-gage and beyond the outer ends thereof, said guards also warping from a point intermediate their ends gradually closer to said 110 platen toward their outer ends.

JOHN C. DOANE.
